(57) **CLAIM**

The ornamental design for a smart card, as shown and described.

DESCRIPTION

FIG. 1 is a perspective view of a smart card showing the design.

FIG. 2 is a top plan view of the smart card of FIG. 1.

FIG. 3 is a bottom plan view of the smart card of FIG. 1.

FIG. 4 is a left elevational view of the smart card of FIG. 1.

FIG. 5 is a right elevational view of the smart card of FIG. 1.

FIG. 6 is a front elevational view of the smart card of FIG. 1; and,

FIG. 7 is a rear elevational view of the smart card of FIG. 1.

The dash-dash broken lines in the drawings depict portions of the smart card that form no part of the claimed design.
